UNITED STATES PATENT OFFICE.

HEINRICH FRIEDRICH WILHELM FALKENBERG, OF DORTMUND, GERMANY.

OSCILLATING MOTOR

No. 879,091.

Specification of Letters Patent.

Patented Feb. 11, 1908.

Application filed October 12, 1906. Serial No. 338,678.

To all whom it may concern:

Be it known that I, HEINRICH FRIEDRICH WILHELM FALKENBERG, of Dortmund, Germany, Weissenburgerstrasse 16, a subject of the King of Prussia, Emperor of Germany, have invented certain new and useful Improvements in Oscillating Motors, of which the following is a specification.

The invention has for its object distributing means for hydraulic machines with an oscillating piston which produces the reversal of the distributing slide valve. As compared with known devices, the novelty consists in the fact that the distributing slide valve with its reversing member is arranged in a special casing, into which the water under pressure enters, after a partial reversal of the slide valve into the obturating position for the admission of the water under pressure has been effected by the impact of the oscillating piston, and acts upon the reversing part of the slide valve whereby it is displaced into its end position.

By means of the invention, numerous advantages are obtained. Owing to the fact that reversing members with springs are dispensed with, the operation is rendered simpler and more reliable.

A further advantage consists in the fact that the pressure medium acts completely up to the end of each stroke, so that increased efficiency is obtained. A good joint for the distributing gear is likewise obtained. The number of separate parts employed is small. All parts are readily interchangeable and easy to clean. This is a great advantage for the slide valve in order to prevent stopping up.

A further important point is that sticking of the distributing slide valve in its middle position is effectually prevented. There is the further possibility of starting in every position and in this connection it is quite immaterial whether the machine is loaded or not. In addition, other important advantages are obtained as will appear in the course of the description.

In the accompanying drawing the object of the invention is illustrated by way of example as the driving means for washing machines.

Figure 1 represents a vertical section through the machine on the line I—I of Fig. 3. Fig. 2 represents a vertical section on the line II—II of Fig. 3. Fig. 3 represents a horizontal section on the line III—III of

Fig. 2. Figs. 4 and 5 represent a modification of the piston.

The improvement is shown applied to a motor comprising a cylindrical casing provided with the usual cylindrical working chamber 2, and a motive fluid inlet 1. The piston 4 is provided with a hub 27, which extends through upper and lower openings in the flat faces of the casing and is encircled by the usual packing nuts, and the hub is secured on the shaft 14 in the following manner. The upper end of the hub is tapering and split as at 16, and a nut provided with a hand wheel 15 is threaded on to the tapered and split end. It will be evident that by screwing up the nut, the hub will be tightened on the shaft to any desired extent.

At one side of the working chamber as shown in Fig. 3, is arranged a hollow abutment 21 radial of the chamber and extending between the hub 27 and the peripheral wall of the casing. The ends of the abutment are provided with openings 25, through which are adapted to extend projections 26 on the opposite faces of the piston 4, when the said piston is at the end of its stroke in each direction.

The slide valve 5 is arranged to slide on the floor 8 of the abutment, which floor is provided with three passages, the central passage communicating with the exhaust 11 of the casing, and the side passages 22 and 22' discharging into the working chamber 2 of the casing on opposite sides of the abutment as shown in Fig. 1. The upper surface of the slide valve is provided with a seat or saddle 23, received in a groove 24 in a piston 5' arranged above the slide valve and moving therewith, this piston being adapted to move the slide valve by means to be presently described.

The openings 25 before mentioned, are opposite the ends of the piston, as will be evident from an inspection of Fig. 3, and that part of the abutment between the slide valve piston and the hub of the motor piston is provided with three passages, a central passage 29 in communication with the hollow 31 of the abutment and the inlet opening 1, and side passages 30 and 30' leading from the respective ends of the hollow of the abutment toward the hub, and adapted to be connected with the central passage by grooves 28 and 28' in the hub of the motor piston as shown in Fig. 3, when the said piston is in certain positions.

The operation is as follows:—When the motive fluid is admitted through the inlet to the working chamber of the motor, the piston will be oscillated, and when it reaches the position shown in Fig. 3, the projection 26 will extend through the opening 25 and engage the adjacent end of the slide valve piston 5', thus slightly displacing said slide valve piston. At this time, the groove 28 10 connects the passage 30 with the passage 29, permitting the motive fluid to pass through the passage 29, the groove 28 and the passage 30, to the space between the end of the slide valve piston and the end of the abutment, and the motive fluid forces the slide valve to the opposite side of the abutment, thus closing the communication between the inlet and the passage 22, and opening communication between the inlet and the passage 22'. This same movement connects the passage 22 with the exhaust 11 and disconnects the passage 22' which had previously been connected with the said exhaust. The arrangement described may of course 25 vary as desired, in its detail. The discharge passages for the pressure medium may be constructed differently. In place of one discharge passage formed in the slide valve, several might be provided which would be 30 come operative alternately in one end position of the slide valve or the other. The cross-section of the discharge passage in the slide valve or in the casing is preferably so proportioned that the liquid is discharged by 35 the piston with the smallest possible resistance. The coupling of the piston shaft with the driven shaft may be effected by means of a resilient sleeve, which is pressed by means of a hand wheel screwed on to the piston 40 shaft against the driven shaft, whereby the hand wheel and the piston shaft are coupled with the driven shaft. The construction of the auxiliary piston 5' may differ from that here represented in any desired manner. 45 Again, the casing and the arrangement of the passages in the casing may be modified as desired, without thereby necessarily affecting the principle of the invention. The essential point is that in all cases the reversal of the 50 distributing slide valve should take place first by the impact of the piston and then by means of the pressure medium. The surface which the distributing slide valve presents to

the pressure medium must be smaller than the surface of the piston. The projections 55 26 of the piston 4 may be provided with openings 32, 33 (Figs. 4 and 5) which are arranged in such a manner that during the displacement of the valve piston 5 the medium contained in the casing 21 may flow out through 60 those openings 32, 33.

Having now particularly described and ascertained the nature of my said invention, and in what manner the same is performed, I declare that what I claim is:

1. In a motor provided with an oscillating piston, and a slide valve for controlling the motive fluid, of means in connection with the piston for slightly displacing said valve toward reversing position near the end of the 70 oscillatory movement of the piston; and means whereby said displacement will admit the motive fluid behind the valve to complete the reversing movement of the valve.

2. In a motor provided with an oscillating 75 piston, a slide valve for controlling the motive fluid, a hollow abutment in which the slide valve moves, a piston moving with the slide valve in the abutment, the ends of the piston being adapted to contact with the end 80 walls of the abutment, said end walls being provided with openings, projections on the motor piston adapted to extend through said openings whereby to slightly displace said valve piston near the end of each oscillation 85 of the piston, and means whereby said displacement will admit the motive fluid behind the valve piston to complete the reversing movement of the valve.

3. In a motor provided with an oscillating 90 piston, and a slide valve for controlling the motive fluid, means in connection with the piston for slightly displacing said valve towards reversing position near the end of each oscillation of the piston, and means whereby 95 said displacement will cause the motive fluid to complete the reversing movement of the valve.

In testimony whereof I have hereunto set my hand in presence of two subscribing witnesses this 1st day of October 1906.

HEINRICH FRIEDRICH WILHELM FALKENBERG.

Witnesses:

OTTO KÖNIG,

J. A. RITTERSHAUS.

It is hereby certified that in Letters Patent No. 879,091, granted February 11, 1908, upon the application of Heinrich Friedrich Wilhelm Falkenberg, of Dortmund, Germany, for an improvement in "Oscillating Motors," an error appears in the printed specification requiring correction, as follows: In line 55, page 2, the word "position" should read *piston*; and that the said Letters Patent should be read with this corrections therein that the same may conform to the record of the case in the Patent Office.

Signed and sealed this 28th day of April, A. D., 1908.

[SEAL.]

C. C. BILLINGS,
Acting Commissioner of Patents.
